UNITED STATES PATENT OFFICE.

WILLIAM BROOKS TRUITT, OF GREENSBORO, NORTH CAROLINA.

DIVIDING-ENGINE.

997,522.

Specification of Letters Patent. Patented July 11, 1911.

Application filed February 27, 1911. Serial No. 611,220.

To all whom it may concern:

Be it known that I, WILLIAM B. TRUITT, a citizen of the United States, and a resident of Greensboro, in the county of Guilford, 5 State of North Carolina, have invented certain new and useful Improvements in Dividing-Engines, of which the following is a full and clear specification, reference being had to the accompanying drawings, in 10 which—

Figure 1 is a front elevation of my machine complete; Fig. 2 a horizontal transverse section taken through the dividing head; Fig. 3 a side elevation partly in section of the complete machine; Fig. 4 a vertical section through the dividing head; Fig. 5 a face view of the dividing head.

The object of this invention is to provide a simple machine for intermittently feeding 20 a bar or sheet of material, the distance of each movement of the material being predetermined by an adjustable scale arrangement so constructed that any given length of or space on the material may readily and accurately be divided into, and without mental 25 calculation, any desired number of equal spaces within the limits of the apparatus, as more fully hereinafter set forth.

In the embodiment of my invention which 30 I have chosen for the purpose of illustrating the principle thereof, *a* designates a hollow standard and *b* a lever pivotally depending from the upper end thereof and having its lower end connected by a strap or band *c* to 35 a drum *d* mounted loosely on a horizontal shaft *e* journaled in suitable bearings at a distance from the standard and having its axis parallel with the axis of the pivot of the lever. On this shaft *e* is mounted a 40 feed roll *f* which co-operates with an idle feed roll *g* above it, the letter *h* designating the material which is to be fed by these rolls. It will be observed that the act of 45 swinging the lever to the left unwinds the strap *c* from its drum and through the medium of a suitable clutch *i* rotates the feed rolls and thus feeds the material. When this feed stroke is completed, a suitable device, such as a weight *j* hung upon a 50 drum *k* attached to drum *d*, causes the band

c to be rewound upon its drum, the clutch *i* serving to release the drum from the feed shaft and thus avoid feeding the material back again. It will thus be observed that 55 vibration of the depending lever will cause an intermittent feed of the material and that the distance of feed movement will of course be dependent upon the length of lever stroke and the proportion between the drum *d* and the feed roll *f*. 60

It will be understood that any suitable clutch arrangement may be employed and that otherwise the details of the mechanism for translating the vibratory movement of the lever into an intermittent feed movement of the material may be greatly varied 65 without departing from the spirit of my invention.

To vibrate the lever, I employ a rotary dividing head *l* provided with a wrist pin *m* which engages in a longitudinal slot in the lever, whereby with every rotation of the head *l* the lever will be caused to make a complete feeding and non-feeding stroke. The head *l* is affixed to a shaft *n* journaled 70 in a carriage *o* mounted to vertically slide on a standard. A bevel gear *p* on the inner end of the shaft *n* meshes with a bevel gear *q* splined on a shaft *r* vertically mounted within the standard. The lower end of the 75 shaft *r* is provided with a bevel gear *s*, and meshing with this gear is another gear *t* affixed to the inner end of the operating shaft *u*. With this mechanism it will be observed that the head may be conveniently rotated in each of its vertical 80 adjustments. To move the carriage *o* vertically and to lock it in its various positions, I employ a vertical screw *v* journaled in lugs on the standard and working through a 85 threaded lug *w* Fig. 2 on the carriage. The wrist pin *m* is carried by a block *x* sliding in a radial groove in the face of the head, and this block is adapted to be radially adjusted by means of a suitable screw *y* mounted 90 in said groove. 95

It will be observed that with the construction above described the length of the feed stroke of the lever can be varied within the limits of the apparatus. Suitable scales 100

are to be employed for determining the various adjustments. One of these scales, designated a' , is laid off on the standard and is adapted to coöperate with the carriage, and the other scale, designated b' , is marked off on the face of the head in position to determine the radial distance of the wrist pin. It will be obvious that the shortest feed stroke within the limits of the apparatus is obtained by lowering the carriage to the first graduation mark in the scale a' and by shifting the wrist pin to the innermost graduation on the head, and vice versa the longest stroke within the limits of the machine is obtainable by shifting the parts to the opposite ends of the scales. Any suitable scales may be employed and they may be laid off in accordance with well known mathematical principles. The scale a' is preferably what may be called a total-space scale since it is laid off to indicate the spaces or lengths that are to be sub-divided, while the scale on the head may be termed the dividing or sub-dividing scale since it is laid off to indicate the number of parts into which the total-space or length is to be divided. The following examples will illustrate the manner in which these two scales are to be laid off and the manner in which they coöperate: With the scales I have illustrated in the drawings, when the carriage is adjusted to the point 4' on the scale a' and the wrist pin to point 12 on the dividing head, the machine will be adjusted to divide a four foot space into twelve equal parts, that is, into four-inch spaces. Again, should the carriage be adjusted to point 8', which point is exactly half-way between point 4' and the fulcrum of the lever, the machine is adjusted so that it will divide a space eight feet in length into twelve equal parts of eight inches each. Then should the wrist pin be adjusted to point 24 (that is, half-way between 12 and the axis of the dividing head), a space eight feet in length will be divided into twenty-four equal parts of four inches each. In this manner any given total space or length may be readily subdivided into as many equal parts as desired within the limits of the apparatus without mental calculation.

It is obvious that there are several applications of the principle of my invention in practical work, and it is intended that the principle be protected in all applications. The most important of these is to a punching machine, and this being the case I have illustrated at A a portion of a punching apparatus. There is one application of the invention that is especially important. Ordinarily the advancement of h is in a straight line. If h is advanced under a punch while, for example, part m registers with scale

mark 12 on scale b' and o registers with scale mark 4' on scale a' , a line of holes will be punched having a spacing of

$$\frac{4 \text{ feet}}{12} = 4 \text{ inches,}$$

and these holes will be in a straight line. By proper arrangement, however, they may be in a curved line, and it may be necessary that they shall be. For example, on a developed frustum of a cone, the top and bottom are curves of definite radii, and a line of holes for riveting at top and bottom must be on curved lines. These can be readily laid out and punched by my dividing machine. Take an example: Suppose a sheet of metal is to be formed to make the frustum of a cone, as in ordinary steel smoke stack work. Suppose the circumference of this joint at the top line of rivet holes is ninety-five inches or 7'-11" and that the circumference at bottom line of holes is 96 $\frac{3}{4}$ " or 8'-0 $\frac{3}{4}$ ". Suppose the distance from one line of holes to the other is 57 $\frac{1}{2}$ " or 4'-9 $\frac{1}{2}$ ". It is necessary that we have two complete dividing machines and that the rollers between which h passes shall not have very broad faces. One of these sets of rollers must be placed in line with center of punch, and the other 57 $\frac{1}{2}$ inches in front of punch. Set off on one scale a' 7'-11" and on the other 8'-0 $\frac{3}{4}$ ". Set the number of spaces desired on both dividing heads. As the sheet is pulled through by the rollers one side advances 7'-11" while the other advances 8'-0 $\frac{3}{4}$ ". Therefore the curve wanted is generated and the holes punched along that curve. To punch the other side reverse the setting of the levers and the opposite side curve will be generated.

Having thus described my invention, what I claim as new and desire to secure by Letters Patent, is—

1. In a dividing engine, the combination of a support means for feeding the work, a swinging lever connected to said feeding means, a dividing head and means connecting it to said lever, means for rotating said dividing head to reciprocate the lever, means for shifting the dividing head along the length of the lever, means for shifting the connecting means between the lever and the dividing head radially with respect to the dividing head, and two scales on said parts coöperating with each other to determine the position of the parts relatively to each other.

2. In a dividing engine, the combination of a support means for feeding the work, a swinging lever connected to said feeding means, a dividing head and means connecting it to said lever, means for rotating said dividing head to reciprocate the lever, means

for shifting the dividing head along the length of the lever, means for shifting the connecting means between the lever and the dividing head radially with respect to the dividing head, and two scales on said parts coöperating with each other to determine the position of the parts relatively to each other, one of said scales being a total-space scale located to coöperate for positioning

the carriage and the other scale being a sub- 10 division scale and located on the dividing head.

In testimony whereof I hereunto affix my signature in the presence of two witnesses.

WILLIAM BROOKS TRUITT.
